US00D904678S

(12) **United States Design Patent** (10) Patent No.: **US D904,678 S**
(45) Date of Patent: **** Dec. 8, 2020**

(54) **ELECTRONIC VAPORIZER**

(71) Applicant: **Shenzhen Jiapin Jianyi Technology Co., Ltd**, Shenzhen (CN)

(72) Inventors: **Shanhong Wang**, Shenzhen (CN);
Charles Wong, Shanghai (CN)

(**) Term: **15 Years**

(21) Appl. No.: **29/677,616**

(22) Filed: **Jan. 22, 2019**

(51) LOC (12) Cl. **27-62**

(52) U.S. Cl.

USPC **D27/162**

(58) **Field of Classification Search**

(57) **CLAIM**

The ornamental design for an electronic vaporizer, as shown and described.

DESCRIPTION

FIG. 1 is a front view of the present invention.

FIG. 2 is a right side view of the present invention and the left side view of the present invention is a mirror image of the right side view.

FIG. 3 is a rear view of the present invention.

FIG. 4 is a front right side view of the present invention.

FIG. 5 is a front left side view of the present invention.

FIG. 6 is a top front perspective view of the present invention.

FIG. 7 is a top rear perspective view of the present invention.

FIG. 8 is a bottom front perspective view of the present invention.

FIG. 9 is a bottom rear perspective view of the present invention.

FIG. 10 is a top view of the present invention; and,

FIG. 11 is a bottom view of the present invention.
